VISIBLE MARGIN-STOP SETTING MECHANISM FOR TYPEWRITERS

Frederick W. Schremp, Stamford, and Edward J. Yeo, Norwalk, Conn., assignors to Remington Rand Inc., New York, N. Y., a corporation of Delaware

Application July 5, 1950, Serial No. 172,038

4 Claims. (Cl. 197—63)

1

This invention relates to improvements in typewriting and like business machines of the type wherein the extent of paper carriage travel is predetermined by adjustable margin-stops which are selectively positionable along a toothed supporting rack extending longitudinally within the carriage.

The present invention comprehends the provision of new and novel margin-stops which are particularly designed and located in such a manner that at least a portion thereof is visible in front of the paper table at all times; which do not in any way interfere with proper feeding of paper over the paper table; margin-stops having an index or pointer cooperating with a margin scale on the lower part of the paper table; and stops which afford economic fabrication and facilitate finger-release manipulation during positioning the stops selectively along their supporting rack without the necessity of manipulating any other parts of the typewriter, or reaching behind the paper table, as is now the customary practice with stops concealed beneath the paper table.

Other objects of the invention will be pointed out in the following description and claims, and illustrated in the accompanying drawings, which disclose, by way of example only, the principle of the invention and the best modes, which have been contemplated, of applying that principle.

In the drawings:

Fig. 1 is a top plan view of a typewriter carriage, with certain parts omitted and other parts broken away in the vicinity of the right-hand margin-stop and center stop, to facilitate illustration of the right-hand stop in top plan.

Fig. 2 is a perspective view of one of the margin-stops and fragmentary portions of the toothed supporting rack.

Fig. 3 illustrates an enlarged front elevational view of the margin-stop shown in Fig. 2 as it will appear when released for sliding adjustment upon the toothed supporting rack.

Fig. 4 is an enlarged transverse vertical section of the paper carriage taken along a plane indicated by the line 4—4 of Fig. 1, looking in the direction indicated by the arrows.

Fig. 5 is an exploded perspective view illustrating a margin-stop of modified construction.

Fig. 6 is a vertical transverse section of the stop, in normal locked position upon the toothed supporting rack, taken on a plane indicated by the line 6—6 of Fig. 5, and

Fig. 7 is a sectional view similar to Fig. 6 illustrating the stop as it will appear when in un-

2

locked position relative to the toothed supporting rack.

The invention, as illustrated, is embodied in a Remington typewriter of the portable class, and the drawings show only such conventional parts of the typewriter as are deemed necessary to make clear the manner of applying the margin-stops and stop-setting mechanisms to typewriters generally.

- 10 Attention is now directed to Figs. 1 and 4, wherein a portable typewriter carriage is indicated generally by reference character A. The carriage includes a stamping comprising a base 10, having end plates 11 and 12 bent upwardly therefrom, and tracks 13 bent downwardly therefrom. The carriage A and tracks 13 are supported for letter-spacing and return movements upon tracks 14, by means of ball bearings 15. The tracks 14 are attached to and between the typewriter side frames 16 by any suitable fastening means, such as screws 17. A platen or cylinder 18 is mounted for rotation between the carriage end plates 11 and 12, and a paper trough 19, suitably supported by base 10, extends under and upwardly to the rear of platen 18 as clearly illustrated in the sectional view Fig. 4. All parts thus far described may be of any well known or conventional construction, as they form no part of the instant invention.
- 15
- 20
- 25

30 Margin-stop mechanism

- As previously stated, it is an object of this invention to provide a structure wherein at least a portion of the adjustable margin-stops is always visible in front of the paper table instead of being concealed from view beneath said table. To this end the paper table, indicated generally by reference character B, has been designed in two parts indicated at 8 and 9 respectively. Lower part 8 has a pair of ears 20 formed integral therewith which are attached to the carriage end plates 11 and 12 by screws 21. A scale 22, calibrated in letter-spaces and inches, is located on the front surface of lower part 8, of paper table B, as clearly shown in Fig. 1. Upper part 9, of paper table B, is attached to the end plates 11 and 12 by flanges 23 and screws 24, the screws being received by threaded holes in flanges 25 bent outwardly from the carriage end plates 11 and 12 respectively. The paper table portion 26, of upper part 9, is further supported by tongues 27 received by slots 28 punched in the lower part 8 of said paper table B.
- 40
- 45
- 50

It will be observed, from the sectional view Fig. 4, that the upper edge 29 of lower part 8, is

spaced forwardly from the lower edge 30 of portion 26, thus providing a horizontally disposed slot-like space C in the paper table B for reasons presently disclosed.

Suitably supported by and between the carriage end plates 11 and 12, is a margin-stop supporting rack D the lower edge of which is provided with teeth 31. A right-hand margin-stop E and left-hand margin-stop F are each slidably mounted upon the rack D, and each stop is supplied with a rearwardly projecting lug or ear 32 for cooperation with a center stop 33 in a well known manner.

According to the disclosed embodiment of the invention, the left-hand margin-stop member F, as shown in Fig. 3, includes a substantially C-shaped frame 34, the legs 35 of which have rectangular slots 36 to receive the rack D. An ear 37 is bent outwardly from the bottom of each leg 35 to assure a smooth sliding movement of the stop on rack D. Rear wall 38 of stop F is provided with an off-set stationary arm 39 having a forwardly bent finger-piece 40 formed integral with its free end. An off-set movable arm 41, pivotally mounted upon a stud 42 anchored to wall 38, has a vertically disposed lip 43 which is normally held in locked engagement with the teeth 31 of rack D, by a spring 44. The upper end of spring 44 is anchored in a hole in the off-set part of stationary arm 39, and its lower end is anchored in an off-set portion of movable arm 41 as clearly illustrated in Fig. 3. Movable arm 41 is further provided with a finger-piece 45, and sidewardly projecting elements 46 and 47. Element 46 merely serves to cover the space between the arms 39 and 41 respectively when they are in normal locked position and element 47 serves as a stop to limit clockwise movement of arm 41 on its pivot stud 42, when the stop F is removed from rack D. The construction is such that when lip 43 bottoms between two adjacent teeth 31, to lock the stop on the rack, there is a slight clearance between the end of element 47 and leg 35 of the stop frame 34.

The construction of right-hand margin stop E is identical to that of the left-hand stop F except that an arm 48 projects downwardly from the wall 38 to operatively engage with the bell ringing arm (not shown) in the conventional and well known manner.

A modified construction, for the margin-stops E and F, is illustrated in Figs. 5, 6 and 7. As shown best in the exploded view Fig. 5, the modified margin-stop, designated generally by reference character G, comprises a frame having a rear wall 49 from which legs 50 are bent, each leg having a rectangular opening or slot 51 to receive the supporting rack D. Each leg 50 has a pair of outwardly bent ears 52 to assure a smooth sliding movement of the stop upon rack D. A pair of bracket arms 53 bent laterally from the upper edge of wall 49 terminate in up-standing ears 54 having aligned holes to receive a pivot pin 55. Pivoted at its forward end, upon the pin 55, and between ears 54 is a U-shaped link 56, and a finger-piece 57 is made rigid with the link by a rivet 58. The rear end of link 56 is pivoted to ears formed integral with the upper end of arm 59, by a pivot pin 60, and the lower end of said arm has a vertically disposed lip 61, which is normally held engaged with the teeth 31 of rack D, by a spring 62. The upper end of spring 62 encircles the head of rivet 58 as best shown in Figs. 6 and 7, and seats upon the lower surface of link 56, while the lower end of said

spring fits over a projection formed integral with the upper edge of rear wall 49. Arm 59 is guided for vertical movement within a notch formed in the ear 63 struck inwardly from the lower edge of wall 49. When stop G is mounted upon rack D, the rack serves to slidably retain arm 59 within the notch in ear 63.

Operation

From the above description, taken in connection with the drawings, it will be obvious that arms 39 and 41, of margin-stops E and F respectively, project upwardly through the slot-like space C in paper table B at all times, and that location of the stops can readily be determined by means of the index point H on the stationary arms 39 in cooperation with the scale 22 on the lower part 8 of the paper table B. It will further be apparent, that to move or shift the stops to any selected position upon the rack D, an operator merely grasps the finger-pieces 40-45 as illustrated in Fig. 3 and by pinching them together, arm 41 is rocked counter-clockwise on its pivot 42, stretching the spring 44 and disengaging the lip 43 from the rack teeth 31, thus permitting the stop to be moved to any desired setting upon rack D relative to scale 22. When a stop has been positioned to the desired location upon rack D, arms 39-41 are then released to permit spring 44 to reengage lip 43 with rack teeth 31 and lock the stop in adjusted position upon the rack.

Manipulation of the modified stop G shown in Figs. 5, 6 and 7 is slightly different from that just described in connection with stops E and F. To release the modified stop G, from rack D, an operator simply presses rearwardly upon finger-piece 57, which in turn rocks link 56 on its pivot 55, driving arm 59 downwardly against the tension of spring 62 to disengage lip 61 from the rack teeth 31 of rack D. While continuing to press rearwardly, on finger-piece 57, the stop may be moved to any desired setting along the rack D by observing the index point H in cooperation with the scale 22. It will be further observed that finger-piece 57 projects upwardly through the slot-like space C, in paper table B, as shown in Figs. 6 and 7, in a manner similar to the projecting arms 39-41, of stops E and F.

While two particular embodiments of the invention have been shown and described, it will be apparent to those skilled in the typewriter art that numerous variations and modifications may be made in the particular construction without departing from the underlying principles of the invention. It is therefore desired, by the following claims, to include within the scope of the invention, all such variations and modifications whereby substantially the results of the invention may be obtained by the use of substantially the same or equivalent means.

Having thus described our invention, what we claim as new and desire to secure by Letters Patent is:

1. In a visible margin-stop setting mechanism for typewriting machines and the like, the combination of, a paper carriage; a paper table supported by the carriage having a slot-like aperture extended longitudinally thereof; a toothed supporting rack mounted within said carriage and in vertical alignment with said aperture; a margin-stop mounted for sliding movement on said rack; and manually operable means pivoted upon said stop including a lip adapted to normally engage selective teeth of said rack to lock the stop thereon, characterized by the fact that at least a por-

tion of said manually operable means projects upwardly through said aperture and in front of said paper table whereby it can be grasped by an operator to free the stop and move it along the rack when adjustment of the stop relative to the rack is desired.

2. In a visible margin-stop setting mechanism for typewriting machines and the like, the combination of, a carriage; a paper table having a slot-like aperture extending longitudinally thereof; scale graduations adjacent said aperture; a toothed rack below said table and in vertical alignment with said aperture; a margin stop adjustably mounted on said rack; an indicator point on the stop to register with said scale graduations; an arm pivoted upon said stop; locking means on said arm engageable with selected teeth of said rack for normally holding the stop in adjusted position upon the rack; and manually operable means carried by said arm and projecting upwardly through said aperture in front of said table, for releasing said locking means when adjustment of the stop along the rack to a selected position relative to said scale graduations is desired.

3. In a visible margin-stop setting mechanism for typewriting machines and the like, the combination of, a carriage; a paper table having an aperture extending substantially from end to end thereof; letter space graduations on said table adjacent to said aperture; a toothed margin-stop rack behind said table and below said aperture; a margin stop slidably mounted on said rack in letter spacing direction; an arm fixed to said stop and projecting upwardly through said aperture; an index point on said arm to register with said graduations on said table; a second arm pivoted upon said stop also projecting through said aperture; and locking means on said second arm normally engaged between selected teeth of said rack

to hold the stop in adjusted position, characterized by the fact that said fixed and pivoted arms respectively are at all times visible in front of said table, and when the pivoted arm is moved towards the fixed arm, the stop is unlocked and free to be moved along the rack to any desired adjusted position relative to said letter space graduations.

4. In a margin-stop setting mechanism for typewriters and the like, the combination of, a carriage; a paper table provided with a slot-like aperture extending longitudinally thereof; graduations on said table adjacent said aperture; a toothed margin-stop rack behind said table and below said aperture; a margin-stop slidably mounted upon said rack; a link pivotally connected to said stop; an arm pivotally connected to said link; locking means carried by the lower end of said arm for engagement with selected teeth of said rack, to hold the stop in adjusted position; spring means acting to normally hold said locking means engaged with said rack; and a finger-piece fixed to said link and projecting upwardly through said aperture, and in front of said table, which when pressed towards said table, releases said locking means to free the stop for movement along the rack to any desired adjusted position with respect to said graduations.
